[57] ABSTRACT

An oven of the continuous-cleaning type in which the oven door therefor is provided with a muffle panel to which a continuous-cleaning coating is applied while the portion of the door inner panel which borders the muffle panel has a smooth-surfaced porcelain enamel applied thereto.

FIG. 1

FIG. 3

FIG. 4

FIG. 2

DOOR FOR CONTINUOUS-CLEANING OVEN

CROSS-REFERENCE TO RELATED
APPLICATIONS

Applicant is unaware of any related patent applications.

BACKGROUND OF THE INVENTION

1. Field of the Invention

The invention pertains to the art of oven constructions and pertains particularly to an oven door construction for a continuous-cleaning oven.

2. Description of the Prior Art

U.S. Pat. Nos. 3,266,477, and 3,465,023, teach the application of a coating composition to the parts of an oven cavity exposed to oven heat for the purpose of facilitating oxidation of food soils on the surfaces at temperatures in the order of those encountered in ordinary cooking operations in a cooking oven. The teachings of these patents call for the incorporation of catalytic agents in the coating compositions to promote the oxidation of the food soils on the oven wall surfaces. Other coating compositions which presumably do not include catalytic agents are also available for coating oven cavity surfaces, an example of one such composition being that produced and commercially available from the Glidden-Durkee Division of SCM Corporation. The compositions of materials which function to promote oxidation of food soils at the temperatures in the order of those normally encountered in ordinary cooking operations in an oven are characterized as continuous-cleaning compositions for the purpose of this application.

All of the coatings of the continuous-cleaning type of which I am aware provide a relatively dull or matte finish and are relatively abrasive (i.e., non-smooth) in nature. So far as I am aware also, the typical oven door for a continuous-cleaning oven includes the coating on both the muffle panel and the part of the inner panel of the door which provides a border around the muffle panel. Since this border is not directly exposed to the oven heat when the door is closed, the continuous-cleaning composition thereon does not function adequately to yield the continuous-cleaning desired.

SUMMARY OF THE INVENTION

Stated relatively simply, in accordance with my invention, the muffle panel for the oven door constitutes a part separate from the inner panel of the door with the muffle panel coated on its oven facing surface with a continuous-cleaning coating, and with the portion of the inner panel bordering the muffle panel being provided with a smooth-surface, porcelain enamel material, and with the muffle panel being attached to the remainder of the door with thermal insulation interposed between the muffle panel and inner panel. As a result, the muffle panel tends to retain its heat which promotes the oxidation of the food soils of the muffle panel, while the smooth-surface border portion of the inner panel, which is not subjected to the direct exposure to oven heat, can be readily wiped clean to the extent it accumulates food soils.

DRAWING DESCRIPTION

FIG. 1 is a perspective view of a cooking range having an oven and oven door according to the invention;

FIG. 2 is a partly-broken face view of the inner face of the door of FIG. 1 illustrating one form of door construction which may be used, this view including stippling on a portion of the muffle panel to denote a continuous-cleaning coating and with a portion of the border about the muffle panel being provided with a representation indicating the smooth-surface porcelain enamel;

FIG. 3 is a sectional view corresponding to one taken along the line III—III of FIG. 2; and

FIG. 4 is a sectional view corresponding to one taken along the line IV—IV of FIG. 2 and showing one form of means which may be used for fastening the muffle panel to the inner panel.

Referring to FIG. 1, the cooking range shown is of the type which includes an oven of the continuous-cleaning character. The oven cavity 10 is defined by opposite side walls 12 and 14, top and bottom walls 16 and 18, and rear wall 20. The throat of the oven cavity is defined by the generally outwardly-directed flanges 22 of the oven liner, these flanges including portions projecting slightly forwardly of the plane of the bordering front face 24 of the range body to form a rim. Conventional heating elements (not shown) are also provided in the oven.

The open front face of the oven cavity is adapted to be substantially closed by the oven door generally designated 26 and which includes the following parts of particular interest in connection with the invention; the inner panel 28, the muffle panel 30, and the thermal insulating and sealing gasket 32.

The general structural arrangement of the door and the manner in which the various pieces are attached to each other is the same as that taught in Tilus, U.S. Pat. No. 3,439,668 and is simply one example of a way in which the muffle panel may be attached to the remainder of the door and hold the thermal insulating sealing gasket 32 in place between the rim of the muffle panel and the opposing face of the inner panel. Accordingly, the structural arrangement will be only described in general terms, and reference should be had to the noted patent for details of that particular structural arrangement.

As shown in FIGS. 2-4, the muffle panel 30 has the shape of a relatively shallow pan which is secured at its four corners through the means of brackets 34 welded to the hidden surface of the muffle panel, and bolt 36, to areas of the inner panel adjacent the cut-out portion 38 of the inner panel.

The gasket 32 may take various forms, but as illustrated in the drawing it is an open-ended, woven glass or asbestos fiber sleeve which is generally circular in an unstressed form, but as supported and held in the illustrated construction, takes a flattened form. The gasket is held in a shape to fit and be clamped between the muffle panel rim and the exposed face of the inner panel by a wire frame 40 inside the gasket. The illustrated gasket extends without interruption along three sides of the cutout 32 area of the inner panel, and along the fourth side adjacent the hinged edge of the door the gasket terminates near the corners of the muffle panels to provide an air inlet slot between the door and the front face of the range body when the door is closed.

When the door 26 is closed, the muffle panel projects slightly into the interior of the oven at the oven throat. The gasket 32 abuts the oven liner flanges 22 to pro-

vide a seal between the door and the front face of the range except in the interrupted area of the gasket. The areas of the inner panel 28 which border the muffle panel and gasket are not directly exposed to the oven heat, but to the contrary are in facing relation with the border area 24 at the front face of the range.

At least some of the walls 12-20 of the oven cavity have a continuous-cleaning coating applied thereto to facilitate the oxidation of the food soils at those temperatures in the order of the temperatures encountered in ordinary cooking operations in an oven. The continuous-clean coatings are denoted in the drawing by stipple areas 42 shown on portions only of the walls. It will be understood that to the extent the coating is applied to a given wall, it will typically be applied over the entire surface of the wall facing the oven interior.

In accordance with the preferred construction of the invention, the muffle panel 30 of the door comprises a part separate from the remainder of the door. The surface of the muffle panel facing the oven interior is also coated with the continuous-cleaning composition, also indicated by the stipple representation 42 shown on only a portion of the muffle panel. Such a coating in its present state of development tends to have a matte surface (i.e., dull and non-smooth) which is somewhat rough or abrasive to the touch. In contrast to this coating, the face of the inner panel border surrounding the muffle panel is provided with a conventional smooth-surface porcelain enamel indicated by the glassy representation 44 shown in the drawing as being on only a part of the border, it being understood that it is applied to the entire border surface exposed to view.

With this arrangement of the difference in coatings of the parts, coupled with the substantial thermal insulation between the muffle panel and the inner panel, an improved arrangement is provided. Since the muffle panel is directly exposed to the oven heat, but is thermally insulated from the inner panel so that conduction of heat from the muffle panel is minimized, the functioning of the continuous-cleaning coating is promoted. However, since the border area of the inner panel is not exposed to the oven heat and accordingly has a relatively lower temperature at which the continuous-

cleaning coating would be ineffective for practical purposes, the continuous-cleaning coating is omitted from the border area and the inner panel is simply provided with a smooth-surface porcelain enamel from which food soils deposited thereon can be removed more easily by wiping than from a continuous-cleaning coating.

What is claimed is:

1. A cooking oven including:

an oven cavity formed of opposite sides, top, bottom and rear walls, and having a throat at its front face; a continuous-cleaning coating on the inner face of at least some of said walls for promoting the elimination of cooking residues deposited on said walls during cooking by having said continuous-cleaning coating subjected to oven heat; a door for the front face of said oven, said door including;

a muffle panel having a cross-sectional area generally coextensive with, but slightly smaller than, said throat so as to be received therein, an inner panel having said muffle panel fixed thereto, said inner panel including a border portion outwardly of said muffle panel, a continuous-cleaning coating on the oven facing surface of said muffle panel, and a relatively smooth-surface porcelain enamel on said inner panel border portion.

2. A cooking oven according to claim 1 including:

thermal insulating means interposed between said inner panel and said muffle panel to provide heat break means therebetween.

3. In a cooking oven door construction of the type having a muffle panel, and inner panel bordering the muffle panel and dimensioned so that said border is not exposed to the interior of said oven when said door is in a closed position:

a continuous-cleaning coating on the oven facing surface of said muffle panel; a relatively smooth surfaced porcelain enamel coating on said inner panel border portion; and thermal insulating means interposed between said inner panel and said muffle panel to provide a heat break therebetween.
